UNITED STATES PATENT OFFICE.

ROBERT SEEGER, OF ST. LOUIS, MISSOURI, ASSIGNOR TO NEW PROCESS OIL COMPANY,
A CORPORATION OF MINNESOTA.

APPARATUS FOR TREATING HYDROCARBON OILS.

1,394,688.

Specification of Letters Patent. Patented Oct. 25, 1921.

Application filed September 15, 1917. Serial No. 191,536.

To all whom it may concern:

Be it known that I, ROBERT SEEGER, a citizen of the United States of America, residing at the city of St. Louis, State of Missouri, United States of America, have invented a certain new and useful Apparatus for Treating Hydrocarbon Oils, of which the following is such a full, clear, and exact description as will enable any one skilled in the art to which it appertains to make and use the same, reference being had to the accompanying drawings, forming part of this specification.

My invention relates to an apparatus for treating petroleum or other heavy hydrocarbons to produce lighter hydrocarbons therefrom and particularly to an improved form of cracking retort for such apparatus.

In the accompanying drawings which illustrate one embodiment of my invention, Figure 1 is a view, partly in section and partly in elevation, of a furnace showing the arrangement of cracking retorts therein. Fig. 2 is a sectional and diagrammatical view illustrating a cracking retort and associated apparatus, and Fig. 3 is a transverse cross section of the retort of Fig. 2.

The furnace is provided with one or more heating chambers 1, which may be heated in any suitable manner such as by means of fuel burners 2. The lower portions of these chambers communicate, as indicated, with a flue 3 which in turn communicates with the stack 4 at the rear of the furnace.

In each heating chamber is located a plurality of retorts 5. Referring to Fig. 2, these retorts 5 comprise metal tubes, or casings of relatively large diameter provided with closures 6 and 7 and cracking tubes 8 within the casings and connected to form a continuous conduit through which is forced the material to be cracked, which will hereafter be referred to for convenience as "oil." In the form illustrated the casing also contains tubes 9 connected to form a continuous conduit into which water is forced by means of a suitable pump (not shown). The end of the water conduit is open in the casing and preferably the final tube is also perforated. The interior of the casing is connected by means of pipe 10 with a steam drum or reservoir 11, exit of steam from the casing to drum 11 being controlled by valve 12. In Fig. 2, 24 and 25, represent the

front and rear walls respectively of the furnace.

The cracking coil or conduit formed by the pipes 8 is supplied with oil from pipe 13 controlled by the valve 14 and with steam by the pipe 15 controlled by valve 16. The pipe 15 is connected to the steam drum 11 and such quantity of steam as may be required in excess of that furnished to drum 11 through the pipe 10 is supplied to the drum from an auxiliary steam boiler (not shown) by means of the pipe 17. Vapor issuing from the cracking coil is conducted through pipe 18 to the vapor chamber 19 which contains the coil or pipe 20 through which the oil to be treated passes to pipe 13. The hot vapor from the retorts thus serves to preheat, in the chamber 19, the supply of oil to be cracked and it is then conducted to suitable condensers. Pyrometers 21 and 22 serve to indicate the temperature within the retort 5 and within the cracking tubes 8 respectively. The supply tubes of the coils 8 and 9 pass through the closure 7 and detachment of this closure makes it possible to withdraw the coils for repair or replacement without disturbing the casing or the furnace wall.

Each of the retorts 5 in the furnace may be connected to the single steam drum 11 and each retort is constructed as that shown in Fig. 2 and supplied with the water and with oil mixed with steam in a similar manner.

In the operation of the apparatus the heat of the furnace applied to each retort 5 converts the water supplied through pipes 9 into super-heated steam which in turn heats the cracking tubes 8. Preheated oil mixed with steam is introduced into the cracking tubes and the pressure in these tubes is maintained relatively high, preferably from 5 to 10 atmospheres, according to the material to be cracked. This pressure is controlled by the oil supply pump and the exit valve 23. The pressure of the steam in the retort is preferably maintained at a point approximating the pressure in the cracking tubes. This arrangement relieves the walls of the tubes from bursting pressure and makes it possible to use much lighter and less expensive tubing. Moreover, the arrangement described tends to maintain a more uniform degree of heat throughout all parts of the

entire cracking conduit and experiments have shown that tubes so heated operate more efficiently and satisfactorily to crack the oil than similar tubes exposed to the direct heat of the furnace. Warping of the cracking tubes is also minimized and their durability increased.

As a modification I may fill the casings 5 with nitrogen or other gas and seal them, 10 thus dispensing with the water tubes 9. When gas is employed only a sufficient quantity will be used to produce the desired pressure at the highest temperature to which it will be subjected. As another modification, 15 a metal or alloy having a low melting point may be employed in the casings and steam or gas introduced only to sufficient extent and for the purpose of maintaining an exterior pressure on the cracking coils.

20 Having fully described my invention, what I claim as new and desire to secure by Letters Patent of the United States is:

1. In apparatus of the class described, a cracking retort comprising a casing and cracking tubes within the casing, but not 25 communicating with the interior thereof, means for maintaining the contents of the tubes under pressure, and means for keeping the casing filled with liquid or gas under a pressure approximately equal to the pressure within the cracking tubes. 30

2. In apparatus of the class described, the combination of a casing, a removable closure therefor, a cracking coil within the casing, supply and discharge tubes for the cracking 35 coil passing through the removable closure, and water supply and steam discharge conduits communicating with the interior of the casing and also passing through the removable closure. 40

In testimony whereof, I have hereunto set my hand and affixed my seal.

ROBERT SEEGER. [L. s.]
